UNITED STATES PATENT OFFICE.

THOMAS H. SEELY, OF BOSTON, MASSACHUSETTS, ASSIGNOR TO UNITED SHOE MACHINERY COMPANY, OF PATERSON, NEW JERSEY, A CORPORATION OF NEW JERSEY.

INSOLE-REINFORCING MACHINE.

1,149,297.

Specification of Letters Patent.

Patented Aug. 10, 1915.

Application filed November 12, 1914. Serial No. 871,818.

To all whom it may concern:

Be it known that I, THOMAS H. SEELY, a citizen of the United States, residing at Dorchester, Boston, in the county of Suffolk and State of Massachusetts, have invented 5 certain new and useful Improvements in Insole-Reinforcing Machines; and I do hereby declare the following to be a full, clear, and exact description of the invention, such 10 as will enable others skilled in the art to which it appertains to make and use the same.

This invention relates to machines for applying reinforcing material to insoles which 15 are used in the manufacture of boots and shoes, and more particularly to mechanism for trimming the excess reinforcing material while it is being applied to the insole.

Heretofore, in using machines of the character referred to, the reinforcing material 20 has been formed about the lip and applied along the margin of the insole, step by step, and as the insole progresses through the machine cutters, guided by the contour of the 25 insole, trim the reinforcing material along a line coinciding with its edge. One such machine is that illustrated and described in the United States patent to J. B. Hadaway No. 614,860, dated November 29, 1898. 30 After the insole is reinforced and the fabric is trimmed in the manner described in said patent the edge of the reinforcing material often becomes loosened from the feather and its edge raveled out so that the threads of 35 the fabric show beyond the edge of the insole when viewed from its grain side. This condition is undesirable as it renders the insole unsightly and detracts from its selling qualities.

40 The object of the present invention is to improve the fabric trimming mechanism so as to overcome the disadvantages heretofore experienced in trimming the fabric along the edge of the feather.

45 In accordance with this object, the invention contemplates the provision, in a machine of the character described in said Hadaway patent hereinbefore referred to, of rotary fabric trimming knives constructed 50 and arranged so as to sever the fabric along a line within the edge of the insole instead of coincident with said edge. In carrying out the object of the invention the fabric trimming cutters of said patent have 55 been utilized, changes being made in the

construction and arrangement of their operating mechanism so as to effect a severance of the fabric along a line spaced from the edge of the insole.

The various features of the invention will 60 be best understood from an inspection of the accompanying drawings illustrating the preferred embodiment of the invention, in which—

Figure 1, is a side elevation of the machine looking from the right and has parts about the trimming knives removed in order to show the improved trimming knives; Fig. 2 is a detail view showing the relation of the trimming knives to the insole during 70 the trimming operation; and Fig. 3 is a front elevation of the parts shown in Fig. 2.

The preferred embodiment of the invention is illustrated as applied to the insole reinforcing machine shown in the patent to 75 Hadaway No. 614,860 hereinbefore referred to, and reference may be had to this patent for a detailed description of the machine and its mode of operation. As described in said patent, a head frame A' mounted on a 80 base A carries the reinforcing tools and their operating mechanism. In this frame is also mounted a work support C which is held yieldingly in working position. An insole having a piece of reinforcing fabric 85 roughly applied to its lipped face is placed upon the support C, which may be lowered through means of a treadle attached to c², with its lip against the beading finger e² of the former E. The projecting margin of 90 the reinforcing material rests on the top of the beading finger. When in operating position the insole is clamped between the support C and a bead forming tool which bears upon the reinforcing material on the feather 95 of the insole. Rotation of the main cam shaft B forces the presser tool D against the reinforcing material upon the face of the insole by means of its connection with cam b⁵ and tucks the material against the inner 100 fact of the lip. From this point a forming tool F forced downwardly through the medium of a cam b⁶ and by coöperation with a finger f' presses the reinforcing material down along the outer side of the lip completing the formation of a bead or crimp about the lip, while the stationary forming tool behind the forming tool F presses the reinforcing material down upon the feather. The drum b² carries a cam which 110

105

is connected with the lever c^{10} and this lever actuates a pawl c^8 for rotating the support C step by step so that after the material has been pressed down upon the insole the 5 presser tool D is raised releasing the insole and a slide f^{10} moves the forming tool F forward simultaneously while the support C is rotated by the pawl c^8 . After the tool F has finished its forward stroke it is raised 10 and returned to its former position ready to repeat its operation on the insole preparatory to making another step.

All of the parts just described may be, and preferably are, substantially the same 15 as the corresponding parts in the Hadaway patent.

The trimming mechanism to remove the excess reinforcing material from the edge of the insole, which forms the subject matter of the present invention, comprising the rotary disk cutters m , m' and their operating mechanism, is mounted in the rear of the support C and as the insole with the reinforcing material attached thereto is fed forward the knives sever this excess material. The cutter m is carried upon the forward end of the shaft 2, and the cutter m' upon the forward end of a shaft 3, these two shafts being mounted in suitable 20 bearings in a carriage 4. The carriage 4 is in the form of a yoke the two arms of which afford a double bearing for both of the shafts. The shafts 2 and 3 are rotated simultaneously in opposite directions 25 by means of a pinion 13 mounted upon the driving shaft 3 and meshing with a similar pinion on the driven shaft 2. The shaft 3 is extended rearwardly beyond the carriage 4 and has a lateral lug 5 carried 30 by its outer end which is engaged by an actuating arm 6 attached to the inner end of a stud shaft 8 mounted in a bearing 9. The bearing 9 is carried by a standard 10 which is attached to the head A' by means 35 of a block 30 and bolt 31. The shaft 8 is driven by a belt-pulley 11. Rotation of the shaft 8 will impart rotation to the shaft 3 by means of the coupling 5-6 and the shaft 2 will be rotated in the opposite direction 40 from 3 through the medium of the pinions 50 5-6 and 12. 55

The irregular contour of an insole requires that the trimming mechanism shall be capable of a longitudinal movement so that it will follow the edge of the insole in trimming off the reinforcing material. The carriage 4 is mounted to move freely back and forth toward the support C upon a bar 17 which is pivotally connected at 18 to a 60 pair of swinging levers 19 that are fulcrumed at 20 to the head A'. The inner end of the carriage 4 is adjustably connected to the bar 17 by means of a slotted supporting arm 32 and set screw 33 which will 65 allow for adjustment toward and away

from the head A', and the outer end of the carriage is rigidly connected to the bar 17 by means of the supporting arm 34. This mounting of the carriage 4 upon the bar 17 is such that the outer ends of the shafts 2-3 70 are thrown away from the head A' and are raised above the plane of the support C so that the shafts are caused to extend at an angle to the support C (see Fig. 1). This causes the knife m to be located above the feather and inside of the edge of the insole and the knife m' to be located below it in a position to chamfer the edge of the insole when the knives are operated. Consequently the reinforcing fabric is severed 75 along a line inside of the edge of the insole. 80

One of the levers 19 has a projecting arm 21 which is arranged to have a limited movement between the adjustable stop screws 22 threaded in bearings in the lugs 23 on the frame A', and said arm 21 is connected to one end of a spring 24 the opposite end of which is secured in one of the lugs 23. The forward bearing for the lever shaft 3 is squared and has secured thereto a guard frame 25 (Figs. 2 and 3) which is provided with a portion 26 extending over the shaft 3, forming a table over which the marginal portion of the canvas travels as the insole is fed forward. The free end of this bearing has mounted thereon a sole gage 27, shown best in Fig. 3, just in advance of the cutters and opposite their bite. This gage, as is seen, is mounted for adjustment toward the cutters as they wear 90 smaller. The gage 27 prevents the cutters from cutting in too deep, the size of the beveled string chamfered off being determined by a longitudinal adjustment of the guard 25 on the shaft journal. In order to 95 adapt the trimming mechanism for different thicknesses of insoles, the fulcrum 20 of the inner lever 19 is eccentrically mounted upon the frame A' and when the adjustment has been made to determine the vertical position of the knives m and m' the position of the eccentric fulcrum 20 is secured by means of a set screw 35. 100

That the cutting knives m and m' may be kept in proper adjustment and in close contact while traveling along the edge of the insole, the shaft 2 is arranged to have a longitudinal sliding movement in its bearings in the carriage 4. Surrounding this shaft is a coiled spring 14 which bears 115 against the inner end of the yoke of the carriage 4, and at its opposite end against a collar 15 secured upon a shaft 2 so that the spring will normally force the shaft 2 backward in order to keep the cutting edges 120 of the knives in close contact. 125

With the above described mechanism, as the insole with the reinforcing material extending beyond its edge is fed forward against the stationary trimming mecha- 130

nism, the gage 27 will be held against the upper edge of the insole by the spring 24, while the knife *m* will be held by the spring 15 in close contact with the knife *m'*. The 5 spring 24 permits the gage 27 to move in and out in accordance with the width of the feather performing the same function as the corresponding part on said Hadaway patent. When the insole is started through 10 the machine the knives are dug into the upper edge of the feather, as they project beyond the gage which bears on said edge, and consequently their cutting bite is within the edge of the insole. As a result the 15 reinforcing material is trimmed at the inner edge of the bevel produced by the knives, that is along a line inside the edge of the insole. The adjustment of the carriage 4 by means of the slotted bar 32 and the eccentric pin 20 will allow for different thicknesses of feather so that the trimming mechanism is suitable for any size or style of 20 insole.

While the invention has been illustrated 25 and described in connection with a machine for applying reinforcing fabric to insoles, it will be apparent to those skilled in the art that a rotary trimming mechanism mounted at an angle to the work support is equally 30 well adapted to be used for retrimming the fabric after it has once been trimmed along a line coincident with the edge of the insole, and the invention is, therefore, not limited to use in a machine which initially 35 applies the insole reinforcing material.

The nature and scope of the invention having been indicated and its preferred embodiment having been specifically described, what is claimed as new, is:

40 1. An insole machine of the character described, having, in combination, means for supporting and feeding the insole and for operating on the reinforcing fabric at its marginal portion, two coöperating shearing knives constructed and arranged to sever the reinforcing fabric along a line inside the edge of the feather of the insole, and means for operating said knives.

50 2. An insole machine of the character described, having, in combination, a support for an insole, means for feeding the insole and for operating on the reinforcing fabric at its marginal portion, two rotatable trimming knives one above and one below the 55 reinforcing fabric mounted on shafts ar-

ranged at an acute angle to the plane of the support, and means for rotating said shafts.

3. An insole machine of the character described, having, in combination, a support 60 for the insole, means for feeding the insole and for operating on the reinforcing fabric at its marginal portion, a rotatable trimming knife mounted at an acute angle to the plane of the support whereby to bevel 65 the upper edge of the feather and trim the reinforcing fabric, and means to rotate said knife.

4. An insole machine of the character described, having, in combination, means for 70 supporting and feeding the insole and for operating on the reinforcing fabric at its marginal portion, a rotatable trimming knife mounted on a shaft at an angle to the support, and means for adjusting the knife 75 vertically to accommodate different thicknesses of insole.

5. A machine for applying reinforcing fabric to lipped insoles, having, in combination, means for forming a bead or crimp 80 in the reinforcing fabric and securing it to the lip of the insole and the feather, a pair of overlapping trimming knives having their cutting sections located within the edge of the insole whereby the fabric is 85 trimmed along a line inside the edge of the insole, and means for operating said knives to shear the fabric.

6. A machine for applying reinforcing fabric to lipped insoles, having, in combination, means for forming a bead or crimp 90 in the reinforcing fabric and securing it to the lip of the insole and the feather, a pair of overlapping rotary flat disk knives located at the edge of the insole in a plane 95 at an acute angle to the face of the insole, and means for rotating said knives.

7. A machine for operating on reinforced insoles, having, in combination, a support for the insole, means for feeding the insole, a rotatable trimming knife mounted at an acute angle to the plane of the support whereby to bevel the upper edge of the feather and trim the reinforcing fabric, and means to rotate said knife.
